UNITED STATES PATENT OFFICE.

GEORGE G. RICHMOND, OF PROVIDENCE, RHODE ISLAND.

DESIGN FOR COOKING-STOVE.

Specification forming part of Design No. 7,863, dated November 17, 1874; application filed November 18, 1873.
 [Term of Patent 7 years.]

To all whom it may concern:

Be it known that I, GEORGE G. RICHMOND, of Providence, in the county of Providence and State of Rhode Island, have invented a Design for a Portable Cooking Range or Stove, of which the following is a specification:

The nature of my design is fully represented in the accompanying photographic illustration, to which reference is made, in which—

A is the body of the said cooking range or stove. T is the top plate, and H the hearth-plate, all of which are round-cornered and ornamented with a molding, m, composed of a rounded surface, r, within a boundary on each side of angular surfaces d d. The body has also a molding, F, around it near the top, between which and the top are ornamental figures of double crosses E E, &c., in elevated groups, as shown. The doors D are round-cornered, ornamented with a mass of cross-work, C, within a diamond border, G, with a frame-work of intersecting squares or diamonds at the lower corners and center e e e, and of intersecting V-curves at the upper corners and center v v v, all surrounded by ornamental moldings in relief at the edge or margin of the door. The handle J of the door makes a cross

with its shaft B, and is ornamented with crosses in relief on its front. The legs L are ornamented with the intersecting V-curves in relief, with a bulb, I, and border in relief. The panel-work K is like that of the doors, within which the designating name may be placed.

I claim—

1. The combination of the ornaments E and F near the top of the body of the range or stove, as shown and described.
2. The design for a stove-door, having panel ornaments C C, G, e e e, and v v v, substantially as shown and described.
3. The design for a stove-leg, composed of intersecting curves V, forming a border, and surrounding the bulb I, all in relief, substantially as shown and described.
4. The design for a stove-door handle, J, making a cross with its shaft B, and ornamented on its front with crosses in relief, substantially as set forth.

GEORGE G. RICHMOND.
